The ornamental design for a bottle, as shown and described.

DESCRIPTION

FIG. 1 shows a perspective view of a bottle showing my new design;

FIG. 2 shows a front elevation view of the bottle shown in FIG. 1;

FIG. 3 shows a back elevation view of the bottle shown in FIG. 1;

FIG. 4 shows a left side elevation view of the bottle shown in FIG. 1;

FIG. 5 shows a right side elevation view of the bottle shown in FIG. 1;

FIG. 6 shows a top plan view of the bottle shown in FIG. 1; FIG. 7 shows a bottom plan view of the bottle shown in FIG. 1; and,

FIG. 8 shows an inverted perspective view of the bottle shown in FIG. 1.

Broken lines with an evenly spaced dash format illustrate portions of the bottle that form no part of the claimed design. Broken lines with a dash-dot-dash format depict boundaries of the claimed design, and form no part thereof. All areas and broken lines within the innermost solid line on the bottom of the bottle in FIGS. 7 and 8 depict portions of the bottle that form no part of the claimed design.
